UNITED STATES PATENT OFFICE.

SEVERIN F. JENSVOLD, OF DULUTH, MINNESOTA, ASSIGNOR OF ONE-HALF TO OSCAR L. ULVANG, OF DULUTH, MINNESOTA.

SCAFFOLD BRACKET.

Application filed March 4, 1924. Serial No. 696,762.

To all whom it may concern:

Be it known that I, SEVERIN F. JENSVOLD, a citizen of the United States, residing at Duluth, in the county of St. Louis and State 5 of Minnesota, have invented certain new and useful Improvements in Scaffold Brackets, of which the following is a specification, reference being had therein to the accompanying drawing.

10 This invention relates to scaffold brackets for building construction, or similar purposes, and the principal object is to provide as simple and improved construction over that already known as possible, and one that 15 when placed in position on the side of a building can not readily be jarred loose or removed without the removal of the scaffold.

Another object is to provide such a bracket to which a railing may be quickly applied 20 or removed therefrom.

Still another object is to provide novel means whereby the bracing member of such a bracket will be prevented from penetrating beyond reasonable limits the object to which 25 it is applied.

Other objects and advantages of the peculiar structure will appear in the further description of the invention.

Referring now to the accompanying drawing forming part of this application:

Figure 1 is a perspective view of one of the improved brackets as it would appear applied to a vertical wall;

Figure 2 is an enlarged view of the nail 35 engaging end of the scaffold supporting members; and

Figure 3 is another illustration of the nail engaging end of the scaffold supporting members.

40 1 represents the bracing member of the bracket which is preferably constructed of a piece of hollow tubing or pipe, slightly curved and sharpened at its lowermost end as at 2, and curved in a like direction as at 3 at its uppermost end so as to normally project vertically when the bracket is in use.

Just below the curve 3 in the bracket is attached as by a through bolt 4, though somewhat loosely, the angle iron scaffold 50 supporting bars 5, one side of each angle being cut away upon their free ends and the opposite side bent upwardly as at 6 forming an L-shaped terminal in which is formed an elongated slot 7, part of which is in the 55 upturned portion 6 and the other part in the

horizontal portion of each bar, and which latter terminal is enlarged as at 8 so as to freely fit over the head 9 of a common spike or large nail 10 which is first driven into the wall upon which the bracket is to be placed. 60

By this means it is obvious that the bracket must be placed upon the nails 10 (it being assumed that there are two of such previously positioned in the wall for the purpose) by the members 5 being in oblique position 65 as indicated in Figure 3 of the drawings. Then when raised and drawn from the wall the nail heads will slip upwardly into the slots 7 in the upturned portion 6 resulting in a hold which cannot be released without the members 5 being again positioned as when initially applied.

The flat sides of the members 5 being attached to the round member 1 as is obvious will permit of considerable lateral swinging 70 motion thereof so that the spacing of the nails may not have to be accurate.

The lower end of the bracing member 1 is provided with a short piece of angle iron 10', it being loosely attached thereto by a 80 suitable bolt 11 and is for the purpose of preventing the sharpened point 2 of said member protruding too far into a hole or decayed piece of wood, or the ground, when it may be desired to rest the lower end of 85 the member 1 upon the ground.

Within the upper curved end of the member 1 is loosely placed a small piece of pipe 12, or rod if preferred, bent as shown with a U-shaped upper end into which a scaffold 90 railing bar or scantling indicated at 13 in dotted lines may be placed, thus forming a convenient rail for the scaffold.

Having thus described my invention, what I claim and desire to secure by Letters Patent, is:

1. A scaffold bracket of the type described comprising a tubular bracing member pointed at its lowermost end and curved upwardly at the opposite end, two scaffold supporting members pivotally united upon opposite sides adjacent the upper curved end of the bracing member, said supporting members having nail engaging means at their opposite ends, and a removable goose neck rail 100 supporting member within the upwardly curved portion of the bracing member for the purpose described. 105

2. A bracket of the type described comprising a principal bracing member, a pair 110

of angle iron supporting members pivotally attached upon opposite sides of the uppermost end of the bracing member, each of said angle irons having an upwardly turned free end and nail engaging slots within the free ends of the supporting members, said slots being so formed as to prohibit dislodgment of the supporting members from the nails in a horizontal direction, they being re-

movable only when the members are in a **10** substantially vertical position.

In testimony whereof I hereunto affix my signature in the presence of two witnesses.

SEVERIN F. JENSVOLD.
